UNITED STATES PATENT OFFICE.

OTTO NEUSTÄTTER, OF MUNICH, GERMANY, ASSIGNOR TO EMIL NEUSTÄTTER, OF SAME PLACE.

SKIASCOPE-OPTOMETER.

SPECIFICATION forming part of Letters Patent No. 678,435, dated July 16, 1901.

Application filed May 12, 1898. Serial No. 680,509. (No model.)

To all whom it may concern:

Be it known that I, OTTO NEUSTÄTTER, a subject of the Emperor of Germany, residing at Munich, Bavaria, Germany, have invented 5 certain new and useful Improvements in Skiascope-Optometers, of which the following is a specification.

The present invention concerns a new instrument called a "skiascope-optometer," the 10 object of which is both the subjective and objective determination of the refraction, including astigmatism and its meridian. This instrument has the advantage of being a combination of optometer and skiascope, constructed very simply and plainly and so that 15 either as skiascope or as optometer it is superior by special merits to the devices used for either purpose up to date. It allows the lenses to be placed exactly before the eyes of 20 the patient by the operator himself, so adding to the advantages of an optometer those of the trial-set lenses. This same quality 25 also gives to it a superiority over others as a skiascope. The lenses can be combined and interchanged in any way desired, the distance 30 between patient and operator need not to be altered, and the single lenses can easily be replaced.

In the annexed drawings a form of construction of this apparatus is given by way of example.

Figure 1 shows a front view of the instrument. Fig. 2 is a side view of same. Fig. 3 is a transverse section showing the arms 35 kept fixed by the rods. Fig. 4 shows the same section as Fig. 3, but the arms freed from the rods. Fig. 5 is a broken view showing the position of the ophthalmoscope in use. Fig. 6 is a broken front view of the same instrument 40 as the preceding, but arranged for cylindrical glasses. Fig. 7 is a transverse section on the line 7-7 of Fig. 6 through the axis of one of the arms of the instrument shown in Fig. 6. Fig. 8 is a detail showing, on an 45 enlarged scale, the method of securing the adjusting-rods to the supporting-rod. Fig. 8^a is a similar detail showing said rods detached.

The skiascope-optometer shown in Figs. 1, 50 2, 3, and 4 is composed of a cylindrical support-rod H, upon which cylindrical sockets

R are slipped, which can be turned independently of one another and are provided with three arms A A' A'', bearing at their outer extremities suitable frames J, which 55 may be circular or semi-oval or other appropriate form, intended to hold the numbered trial-lenses B. The rod H extends slightly beyond the top socket R, and a pin K passes transversely through its end to hold the 60 sockets on the rod. The latter or its handle is also provided at its lower end with a small horizontal rod c, to the outer end of which two vertical rods S are pivoted. Between 65 said rods the arms A' are placed, and said rods are provided with spring-hooks W at their upper end, these hooks fitting into a corresponding cavity of the rod H, where they are held by a projection T on said rod. The lower part of the rod H bears over the handle b a graduated segment a, in the center 70 of which a hand r is pivoted on an axle-pin d. This arrangement is for use with an ophthalmoscope, as will presently be explained.

The trial-lenses are previously introduced 75 into the lens-frames J of the sockets R in such a way that in every vertical series they are arranged according to their focus powers. Now the sockets must not rotate freely, as in 80 such case the lenses of quite different numbers or powers might range one under the other, and so cause great disorder. On the other hand, the sockets must be allowed to rotate when the instrument is to be used as an optometer. Both these conditions are met 85 by application of the rods S. If all the arms of one vertical series are inclosed between the rods S, the sockets cannot turn at all and the instrument is ready to be used as a skiascope. If they are disengaged by detaching 90 one of the rods S from the hook w at the upper extremity of H and swinging it outwardly and downwardly to allow the passage of the same, then bringing back the rod to its normal position, the sockets cannot rotate any 95 farther than the distance between two arms allows and not so far that lenses of different series get mixed. It is in this latter shape that the instrument is to be used as an optometer. The glasses of the desired series are 100 moved vertically upward or downward one after the other before the eye of the patient

and, if necessary, approached and removed from it by turning to and fro the sockets till the patient has tried the effect of the glass on his sight.

- 5 Should the instrument be employed as a skiascope, the arms of any of the series are left between the rods S and the instrument is moved as before while the operator is observing the change of shade vertically before 70 the eye of the patient naturally without turning the sockets. In astigmatism the main meridians are not always the one horizontal and the other vertical. Thus, for instance, the temporal meridian may be at about thirty 75 degrees with the vertical line. The other meridian is always at right angles with the former, and therefore in the supposed case is at sixty degrees to the nasal side. In the skiascoping operation the shadows move regularly 80 in the eye only if the ophthalmoscope is moved about an axis which is either parallel or at right angles with said meridians. Said axis indicates, therefore, the direction of the meridians. The operator or physician holding 85 the ophthalmoscope vertically before his eye and rotating said device in this position, then when the shadows travel precisely in the patient's eye he knows that the meridians must be vertical or horizontal in presence of astigmatism; but if the ophthalmoscope must be inclined—say from the upper inside to the 90 lower outside—the meridians will be inclined accordingly. Now it must be possible to easily measure such inclinations, because if 95 the physician holds the ophthalmoscope before his eye he does not know the number of degrees measuring the inclination. To this end I have provided the dial α with its hand. The ophthalmoscope (shown at o in Fig. 5) 100 held in its inclination is placed with its central hole upon the axle-pin d, while the skiascope is held in a vertical position. Now the handle of the ophthalmoscope indicates a certain 105 inclination, which is that of one meridian, the other being at right angles therewith. The whole operation is made in a dark chamber, and instead of reading the number of degrees the hand r will be moved until it 110 engages or coincides with the handle of the ophthalmoscope, remaining in this position unless readjusted, and thus enabling the 115 number of degrees to be read lateron. By adjusting two hands instead of one on the axle d it is possible to mark the inclination for both eyes without reading the number between the two operations.

For cylindrical glasses the same instrument may be used with a few modifications, (shown in Figs. 6 and 7,) intended especially to allow 120 the lenses to rotate around their own axes simultaneously. If the instrument is fitted with circular frames, any cylindrical lens which is provided with two or three pins similar to those described hereinafter can be 125 used, supposing that the frame has a suit-

able spring, like F, to hold the lenses, as shown in Fig. 6; but for preventing the lenses from falling out, which may happen by this way of operating, it is better to form the rings serving to hold the glasses so that they can rotate. For this purpose at the extremity of the arms A there is fixed a flat ring R'. In this ring turns a smaller ring with broad outward rims $r' r^2$, one of which, r' , is soldered to it and the other attached by screws. Upon 70 both rims are fixed two or three pins $q' q^2 q^3$, with rounded heads on each of them. These pins serve to retain the glasses, and for this purpose one of them, q , engages a spring-blade F, pressing the glass against one of the others, q' , to fix it and to give a rotating point, which is executed for all glasses together by using the rod S², in which holes are made at intervals equal to the distance between the centers of the adjacent glasses. 75 By placing the rod S² with its holes over the pins of one series and giving a vertical movement to it the disks $r' r^2$, as well as the glasses they bear, turn in the rings R', and so in every position the movement necessary 80 for the inclination of the meridian of corresponding astigmatism can be given to all the glasses at once.

Having fully described my invention, what I claim, and desire to secure by Letters Patent, is—

1. In an instrument of the character described, the combination of a rod provided with a handle, with independent cylindrical rotatable sockets fitted on the rod and provided with radiating arms terminated by frames adapted to hold the glasses, rods pivoted at the lower part of said rod and secured at their upper ends.

2. In an instrument of the character described, the combination of a rod provided with a handle, independent, cylindrical, rotatable sockets arranged on said rod and provided with radial arms arranged in series, glass-holding frames secured to said arms, means for preventing the independent rotation of the radial arms in a single series, a graduated segment secured to said rod, and one or more hands moving over the face of said segment and pivoted to the rod, substantially as described.

3. In an instrument of the character described, the combination of a rod provided with a suitable handle, independent, cylindrical rotatable sockets arranged on said rod and provided with radial arms having glass-holding frames, series of glasses rotatably mounted in said frames and means for rotating the glasses in a single series, substantially as set forth.

OTTO NEUSTÄTTER.
